UNITED STATES PATENT OFFICE.

CHARLES W. DAVIS, OF EDGEWORTH, PENNSYLVANIA, ASSIGNOR TO STANDARD UNDER-GROUND CABLE COMPANY, OF PITTSBURG, PENNSYLVANIA, A CORPORATION OF PENNSYLVANIA.

TERMINAL FOR ELECTRIC CABLES.

No. 898,067.

Specification of Letters Patent.

Patented Sept. 8, 1908.

Application filed December 23, 1907. Serial No. 407,798.

To all whom it may concern:

Be it known that I, CHARLES W. DAVIS, residing at Edgeworth, in the county of Allegheny and State of Pennsylvania, a citizen of the United States, have invented or discovered certain new and useful Improvements in Terminals for Electric Cables, of which improvement the following is a specification.

The invention described herein relates to 10 certain improvements in terminal heads forming the connection between the conductors of a cable and the aerial distributing lines, and has for its object a construction whereby additional aerial lines may be connected to the conductors of the cable as required, without disturbing connections previously formed.

It is a further object of the invention to provide a terminal head consisting of similarly 20 constructed sections or units to be seated one upon another, so that by the use of one or more sections, heads for cables differing widely in the number of contained conductors can be built up.

25 The invention is hereinafter more fully described and claimed.

In the accompanying drawings forming a part of this specification, Figure 1 is a sectional elevation of one form of my improved head; Fig. 2 is a plan view of the underside of the head shown in Fig. 1; Fig. 3 is a perspective view partly in section of another form of head; Figs. 4 and 5 are sectional elevations of other forms of heads.

35 My improved head consists of one or more body sections or units and a cap, the body sections consisting of a conducting core having insulating material molded thereon, the outlet end of the core being in a planeradial 40 or approximately radial to the axis of the cable.

In the construction shown in Figs. 1 and 2, the conducting cores 1 are inclosed in an annular body 2 of insulating material, which is 45 preferably molded onto the cores. The general cross-sectional contour of the annular body is tapering so that the internal diameter of the lower portion 3 of the body is substantially equal to the external diameter of the 50 upper portion 4. When thus constructed and the portion 3 internally threaded and the portion 4 externally threaded, a series of units or sections can be connected together forming a multiple head.

The conducting cores are so shaped and arranged in the insulating material that at one end they project out of the insulating material at points within the outer periphery of the portion 4, while the opposite ends will project from the insulating material at points outside of such periphery. It is preferred that the insulating material inclosing the outer portions of the conducting cores should be made in the form of teats or conical projections 5 so that any moisture collecting thereon will flow down to the points and not towards adjacent cores. These projections are formed in a groove 6, the outer wall of which extends in the form of a petticoat by preference to or below the level of the ends of the teats 5. In applying this head, the lead sheath is removed for a suitable distance and a conical metal sleeve 7 slipped on the cable to a point below the stripped portions and secured to the lead sheath by a wiped joint or in any other suitable manner. A unit or section of the head is then slipped over the end of the cable and screwed onto the threaded end of the sleeve. A number of the conductors are then electrically connected to the inner ends of the cores 1 by any means. In the construction shown the projecting ends of the cores are threaded for the reception of nuts 8 for clamping the cable conductors to the cores. In case it is desired to lead out more conductors than the number of cores contained in one unit or member, a second, and if necessary a third, unit is screwed and put into position successively and the cable conductors attached to the cores. The cap 90 may be formed with a knob 10, which serves as a convenient means for attaching the supporting bracket to the head.

In Fig. 3 I have shown a terminal head consisting of a box or case 11 provided in one side with a tubular projection 12 through which the cable is inserted and to which it is secured by a wiped joint. The end of the box opposite that connected to the cable is removable for the insertion of the units, 95 which in this form of head are made straight. Each unit is provided with a seat 13 outside of the shoulder 4^a corresponding to the portion 4 of the annular head, and a downwardly projecting portion 3^a corresponding to the portion 3 of annular head and adapted, when the units are nested, to rest on the seat 13. In this construction the cores ex-

tend diagonally from the portion 4^a to points outside of the portion 3^a a construction substantially similar to that shown in Fig. 1. The cores pass through teats or conical projections 5 which are protected by a petticoat 14 formed by the outer wall of the groove 6. While these units may be held in proper relation to each other by any suitable means, that shown in Fig. 3 is efficient and consists 10 in grooves 15 in the sides of the box for the reception of ribs 16 on the ends of the units. The front side of the box cover 17 should be made sufficiently long to extend below the upper edge of the upper unit of the series.

15 In Figs. 4 and 5 I have shown a form of my improvement especially applicable to light and power cables containing two or more conductors. Each unit consists of a core 1 of conducting material and a body of 20 insulating material molded thereon. This insulating material is given a disk like shape 18 and is provided on opposite sides with centrally arranged projections 19 and 20 which form seats or supporting portions 25 when the units are arranged one on the other. The core 1 passes through the under projection 20 to a point above the upper surface of the disk and passes out in a substantially radial direction through the side of the upper 30 projection. Each unit has a conducting core molded therein and one or more passages 21 through which the cores of superposed units may be threaded in nesting the units. The number of such passages in any unit will be 35 approximately dependent upon the number of units to be superposed. Each unit can be made with the maximum number of passages and in forming a head all the passages need not be utilized. While not essential 40 the cap or top unit may have a core molded therein and thus form one of the units of the head. In applying this head the cable is stripped and the thimble or sleeve 22 slipped thereon. The required number of units are 45 then arranged one on the other, the cores of the upper units being threaded through the passages of the units occupying a lower position and also through passages in a base block 23. The cores are then connected 50 to the conductors, the thimble or sleeve screwed onto the lower end of the base block and its opposite end secured to the lead sheath by a wiped joint.

I claim herein as my invention:

55 1. A terminal for cables having in combination a body section or unit consisting of a conducting core having a body of self-supporting insulating material molded thereon, the outlet end of the core extending outwardly through the insulating material in a direction radial or approximately radial to the center of distribution, and a cap sup-

ported by the unit and protecting the inner end of the conducting core.

2. A terminal for cables having in combination a series of sections or units similarly constructed and adapted to seat one upon the other, each unit consisting of a conducting core and a body of insulating material molded thereon, the insulating body of one unit extending outwardly beyond the point of emergence of the core of the underlying body.

3. A terminal for cables having in combination a block of insulating material having a seat at one end and a correspondingly shaped portion at its opposite end and a conducting core molded in the insulating block and extending through the insulating block from a point within the seat to a point outside of said seat.

4. A terminal for cables having in combination an annular block of insulating material having a seat at one end and a correspondingly shaped portion at its opposite end, and conducting cores molded in the insulating block and extending through said body from points within the periphery of the seat to points outside of the seat.

5. A terminal for cables having in combination an annular block of insulating material provided at one end with an externally threaded projection and having at its opposite end an internally threaded portion of substantially the same diameter as the externally threaded portion and a series of conducting cores extending through the insulating body from points within the externally threaded portion to points outside of the internally threaded portion.

6. In a terminal for cables, a plurality of body sections or units, each consisting of a conducting core having insulated material molded thereon, the outlet end of the core extending outwardly through the insulating material in a direction radial or approximately radial to the center of distribution, said units or sections being adapted to be seated one upon the other in combination with a cap adapted to cover the top section!

7. A terminal for cables having in combination a block of insulating material, having a seat at one end and a correspondingly shaped portion at its opposite end, and a conducting core extending through said block from a point within the seat to a point outside of said seat.

In testimony whereof, I have hereunto set my hand.

CHARLES W. DAVIS.
